UNITED STATES PATENT OFFICE.

GIUSEPPE BELLUZZO, OF MILAN, ITALY.

ELASTIC-FLUID TURBINE.

No. 910,266.

Specification of Letters Patent.

Patented Jan. 19, 1909.

Application filed December 17, 1906. Serial No. 348,289.

To all whom it may concern:

Be it known that I, GIUSEPPE BELLUZZO, mechanical engineer, subject of Italy, residing at Milan, Italy, have invented new and useful Improvements in Elastic-Fluid Turbines, of which the following is a specification.

The present invention relates to some improvements which can be made use of in any kind of elastic fluid turbines and also in other ones specified hereinafter, which are especially useful when applied to the partial reaction turbines forming the object of my U. S. Patent 814,423 and generally to turbines which work at a very low degree of reaction.

In the drawings—Figure 1 is a sectional view of a partial turbine, the same being broken away to show the position of the blades and mounting thereof; Fig. 2 is a sectional fragmentary view; and Fig. 3 shows a view disclosing a long and short blade and alternately arranged.

The steps taken with the view of reducing such losses often are in contradiction between themselves through the fact that, if the second losses are to be diminished in the turbines, as they are constructed now, the first ones necessarily increase and vice versa. In order to diminish both of them the arrangement shown in Fig. 1 is applied to the, guide wheels d^1 d^2 etc. and to the running wheels r^1 etc.

Between the blades or vanes of normal length P_d and P_r shorter blades or vanes p_d and p_r are interposed, which have the only purpose of deviating the fluid jet.

Fig. 1 shows the application of such an arrangement to a partial turbine made according to the U. S. Patent 814423.

Fig. 3 shows the application thereof to a Parsons turbine. It is evident that instead of disposing alternately one long and one short blade only and so on, the short and long blades can be disposed alternately in different order.

Fig. 4 represents a section of a turbine showing a plurality of wheels arranged successively.

The invention also includes, as already mentioned, an arrangement which relates more particularly to partial and reaction turbines, but which can also be employed for turbines of another type, for instance for turbines of the Curtis type and the

like, when it is desired to remove the walls which separate the different steam chambers.

The blade or vane elements shown in the present embodiment are especially adapted for use in turbines of the type wherein the fluid flows in a direction substantially parallel with the axis of the blade carrying elements, although the invention is not necessarily limited to turbines of such a type, and it will be understood from the foregoing specification that while a single wheel or revoluble blade element is shown, any suitable number of such wheels may be used and arranged alternately with respect to the stationary blade elements as shown in my prior patent aforesaid, instead of a single wheel as shown in the present instance, and such an application of the invention can be readily understood from the present specification, taken in connection with my prior patent aforesaid.

Fig. 4 represents a section of a turbine embodying a plurality of turbine wheels r^1 and r^2 , these wheels being arranged in successive order and are disposed alternately relatively to the stationary blade or vane elements d^1 and d^2 , it being understood that the fluid flows in substantially parallel paths. In this instance, the relatively longer or principal blades or vanes P^1 and P^2 of the wheels and stationary elements, respectively, form spaces that are sub-divided by the intermediate shorter blades or vanes p^1 and p^2 of the wheels and stationary elements, respectively.

The experience proves that it is mechanically very difficult or nearly impossible to cause the running wheels to revolve very close to the guide vanes; on the contrary by leaving between them a certain space of 3 or 4 millimeters, the motion of the elastic fluid is facilitated; and as on the other hand through this space a rather large quantity of steam could escape, it is necessary to provide the ends of the single stationary guide wheels with some kind of steam tight packing. The escape of steam is prevented according to the present invention by making use of a suitable non metallic substance, as for instance graphite or another substance not liable to any alterations when in contact with water steam.

The pieces of graphite or other substances are indicated with a in Figs. 1 and 2 the former of which is an axial section of a

turbine made according to U. S. Patent 814423 as already mentioned, while the latter is an axial section of a Curtis turbine. Said pieces of graphite can be secured to the 5 guide wheels in any suitable way. The said figures show two different manners of fixing these pieces, one by means of a dovetail joint and the other one by means of a washer *b* secured by nails or rivets *c*.

10 It is evident that after revolving for a short period the turbine will without any inconveniences create a very small play by itself, through which only a very small quantity of steam can escape.

15 Now what I claim is:

1. In an elastic fluid turbine, a rotary member having guide blades, and a stationary member having guide blades coöperative with the rotatable member, said guide 20 blades being arranged in series on each of the members, the blades of one series being of less length than those of the other and arranged alternately with respect thereto.
2. In an elastic fluid turbine, a rotary 25 member having guide blades, a stationary member having guide blades coöperative with the rotatable member, said guide blades being arranged in series on each of the members, the blades of one series being of less 30 length than those of the other and arranged alternately with respect thereto and a non-metallic substance associated with the members to form a packing for preventing the escape of fluid from the same.
3. An elastic fluid turbine comprising 35 relatively revoluble elements, provided with blades arranged for a flow of the fluid substantially axially of the elements, some of the blades of one of said elements being of less length than the remaining blades there- 40 of and arranged in the spaces between the said remaining blades.

4. An elastic fluid turbine comprising rotary and stationary blade elements, the stationary element having a set of blades of 45 less length than the remaining blades thereof and arranged in the spaces between them.

5. An elastic fluid turbine comprising rotary and stationary elements, each provided with a series of blades arranged to 50 receive the fluid in flowing substantially axially of the elements, the rotary element having a series of alternately arranged long and short blades, the relatively shorter blades being arranged in the spaces between 55 the longer blades.

6. An elastic fluid turbine comprising rotary and stationary blade elements, both elements having a set of blades of less 60 length than the remaining blades of the series, and arranged in the spaces between the relatively longer blades.

7. In an elastic fluid turbine, rotary and stationary blade elements arranged successively in an axial direction, the stationary 65 elements at each side of the rotary element being each provided with a series of alternately arranged long and short blades, the relatively short blades being arranged in the spaces between the longer blades on the 70 respective stationary element.

8. In a parallel flow turbine having a plurality of turbine wheels, principal stationary vanes forming stationary buckets or vane spaces between successive wheels, and short 75 intermediate vanes subdividing the stationary vane spaces.

In testimony whereof I have signed my name to this specification in the presence of two subscribing witnesses.

GIUSEPPE BELLUZZO.
